VENETIAN BLIND BRACKET

George F. McKerlie, Sturgis, Mich., assignor to
Kersch Company, Sturgis, Mich.

Application March 10, 1941, Serial No. 382,564

7 Claims. (Cl. 156—17)

This invention relates to brackets for supporting Venetian blinds or the like and particularly to such brackets for supporting Venetian blinds having the operating, tilting and lifting mechanism concealed in a channel shaped sheet metal casing. It has for its objects:

First, to provide a new and improved bracket of the type described.

Second, to provide such a bracket with suitable concealing fastening means for holding the ends of the head casing of the Venetian blind against removal and for concealing gaps between the end of the casing and the bracket to give a smooth unobjectionable appearance.

Third, to provide such a bracket which can be made inexpensively from metal stampings and which can be assembled with a minimum of effort.

Fourth, to make such a bracket which can be used at either end of the blind to accommodate either right or left hand fastening members.

Other objects and advantages pertaining to details and economies of construction and operation will appear from the description to follow. The invention is defined in the claims. A preferred embodiment of the invention is illustrated in the accompanying drawing, in which:

Fig. 1 is a front elevational view of one end of a Venetian blind casing supported by the bracket of this invention.

Fig. 2 is a perspective view showing the bracket and the fastening means in open position.

Fig. 3 is an end elevation of the bracket with the fastening means in fastening position.

Fig. 4 is a similar view showing the fastening means in open position and showing in dotted lines the pivotal movement of the fastening means from open to closed position.

Fig. 5 is a view of the blank from which the bracket itself is made.

In Fig. 1, the bracket generally indicated at 1 is shown supporting a regular channel-shaped Venetian blind casing 2. The bracket which is formed of sheet metal consists of a main body portion 3 which is disposed vertically in use. It has a bottom horizontal flange 4 for supporting the bottom of the casing 2 and a top flange 5 and a rear flange 6. Suitable apertures 7 for attachment of the blind to the window casing or the wall are provided.

Adjacent the forward edge of the body portion 3 are a pair of struck up hooks 8 and 9. These hooks are vertically aligned and are opposed to one another.

The fastening member generally indicated at 58

10 consists of a face plate 11 and a right angle flange 12. This flange is provided with an aperture 13 which is adapted to receive the lowermost hook of the bracket as the bracket is installed. One leg 14 of this L-shaped aperture extends parallel with the face plate 11. The other leg 15 extends from the bottom of the leg 14 substantially perpendicularly to and away from the face plate.

10 The L-shaped aperture 13 is so arranged that when the bottom fastening member 10 is in place with the bottom hook 9 in the leg 14 of the opening 13, the face plate 11 is supported in front of, at right angles to and above the supporting flange 4. When it is desired to shift the fastening member from this position to the open position which is shown in Fig. 4, the fastening member 10 is raised as shown in dotted lines in Fig. 3, permitting this fastening member to be moved outwardly and away from the bracket so that the hook 9 passes into the leg 15 of the aperture 13. When this movement has been accomplished, the fastening member can be swung to the lower position shown in Fig. 4 past the dotted line position there shown.

When the fastening member is in position, the flange 12 lies beneath the hook 8.

The flange 12 is cut away as shown at 16 to receive the horizontal flange 4 of the bracket 1 when the fastening member is in the position shown in Fig. 4.

It will be appreciated that when this construction is used only one set of brackets need be produced because the hooks 8 and 9 are identically located with respect to the top and bottom flanges respectively and the front edge of the body portion 3 of the bracket. Either hook will serve to receive a fastening member such as the member 10, it being necessary, however, 40 to have right and left fastening members. The fastening members are easy to install and operate with great ease. They serve to retain the casing of the Venetian blind and to conceal the gaps at the end as shown in Fig. 1. It is possible to have considerable leeway in the length of the casing without having an unsightly installation.

The terms and expressions which have been 50 herein employed are used as terms of description and not of limitation, and there is no intention in the use of such terms and expressions of excluding any equivalents of the features shown and described. It is recognized that various modifications are possible within the scope of the invention claimed.

Having thus described my invention, what I claim as new and desire to secure by Letters Patent is:

1. A bracket of the class described having a vertically disposed body and a horizontal flange at the bottom to receive a Venetian blind head casing or the like, said body having near the forward edge thereof a pair of vertically aligned hooks opposed to one another, and a fastening member comprising a face plate and a right angle flange adapted to lie along the face of said body, said right angle flange having an L-shaped aperture therein to receive the lower one of said hooks and having one leg extending parallel with the face plate flange and the other end extending from the bottom of said first leg substantially perpendicularly to and away from the face plate, said opening being disposed to support said fastening member with a face plate substantially in line with the front of said bracket when the bottom hook is in the first mentioned leg of said opening and to support said fastening member with the face plate below the body of said bracket and parallel with the horizontal flange thereof when said hook is in the other leg of said opening, said flange being cut away adjacent the face plate to provide a recess to receive said flange when the bracket is in said last mentioned position.

2. A bracket of the class described having a vertically disposed body and a horizontal flange at the bottom to receive a Venetian blind head casing or the like, said body having near the forward edge thereof a pair of vertically aligned hooks opposed to one another, and a fastening member comprising a face plate and a right angle flange adapted to lie along the face of the said body, said right angle flange having an L-shaped aperture therein to receive the lower one of said hooks and having one leg extending parallel with the face plate flange and the other end extending from the bottom of said first leg substantially perpendicularly to and away from the face plate, said opening being disposed to support said fastening member with a face plate substantially in line with the front of said bracket when the bottom hook is in the first mentioned leg of said opening and to support said fastening member with the face plate below the body of said bracket and parallel with the horizontal flange thereof when said hook is in the other leg of said opening, said flange having a portion adapted to fit under and be restrained by said other hook when said fastening member is in fastening position.

3. A bracket of the class described having a vertically disposed body and a horizontal flange at the bottom to receive a Venetian blind head casing or the like, said body having near the forward edge thereof a pair of vertically aligned hooks opposed to one another, and a fastening member comprising a face plate and a right angle flange adapted to lie along the face of said body, said right angle flange having an L-shaped aperture therein to receive the lower one of said hooks and having one leg extending parallel with the face plate flange and the other end extending from the bottom of said first leg substantially perpendicularly to and away from the face plate, said opening being disposed to support said fastening member with a face plate substantially in line with the front of said bracket when the bottom hook is in the first mentioned leg of said opening and to support said fastening member

with the face plate below the body of said bracket and parallel with the horizontal flange thereof when said hook is in the other leg of said opening, said flange being cut away adjacent the face plate to provide a recess to receive said flange when the bracket is in said last mentioned position.

4. A bracket of the class described having a vertically disposed body and a horizontal flange at the bottom to receive a Venetian blind head casing or the like, said body having near the forward edge thereof a pair of vertically aligned hooks opposed to one another, and a fastening member comprising a face plate and a right angle flange adapted to lie along the face of said body, said right angle flange having an L-shaped aperture therein to receive the lower one of said hooks and having one leg extending parallel with the face plate flange and the other end extending from the bottom of said first leg substantially perpendicularly to and away from the face plate, said opening being disposed to support said fastening member with a face plate substantially in line with the front of said bracket when the bottom hook is in the first mentioned leg of said opening and to support said fastening member with the face plate below the body of said bracket and parallel with the horizontal flange thereof when said hook is in the other leg of said opening.

5. A bracket of the class described having a vertically disposed body and a horizontal flange at the bottom to receive a Venetian blind head casing or the like, said body having near the forward edge thereof a pair of struck-up vertically aligned hooks opposed to one another, and a fastening member comprising a face plate and a right angle flange adapted to lie along the face of said body, said right angle flange having an L-shaped aperture therein to receive the lower one of said hooks and having one leg extending parallel with the face plate flange and the other end extending from the bottom of said first leg substantially perpendicularly to and away from the face plate, said opening being disposed to support said fastening member with a face plate substantially in line with the front of said bracket when the bottom hook is in the first mentioned leg of said opening and to support said fastening member with the face plate below the body of said bracket and parallel with the horizontal flange thereof when said hook is in the other leg of said opening.

6. A bracket of the class described having a vertically disposed body and a horizontal flange at the bottom to receive a Venetian blind head casing or the like, said body having near the forward edge thereof a hook, and a fastening member comprising a face plate and a right angle flange adapted to lie along the face of said body, said right angle flange having an L-shaped aperture therein, and having one leg extending parallel with the face plate flange and the other end extending from the bottom of said first leg substantially perpendicularly to and away from the face plate, said opening being disposed to support said fastening member with a face plate substantially in line with the front of said bracket when the hook is in the first mentioned leg of said opening and to support said fastening member with the face plate below the body of said bracket and parallel with the horizontal flange thereof when said hook is in the other leg of said opening, said flange being cut away adjacent the face plate to provide a recess to receive said flange when the bracket is in said last mentioned position.

7. A bracket of the class described having a vertically disposed body and a horizontal flange at the bottom to receive a Venetian blind head casing or the like, said body having near the forward edge thereof a hook and a fastening member comprising a face plate and a right angle flange adapted to lie along the face of said body, said right angle flange having an L-shaped aperture therein and having one leg extending parallel with the face plate flange and the other end extending from the bottom of said first leg

substantially perpendicularly to and away from the face plate, said opening being disposed to support said fastening member with a face plate substantially in line with the front of said bracket when the hook is in the first mentioned leg of said opening and to support said fastening member with the face plate below the body of said bracket and parallel with the horizontal flange thereof when said hook is in the other leg of said opening.

GEORGE F. MCKERLIE.
